UNITED STATES PATENT OFFICE.

MILTON M. BLUM, OF BIRMINGHAM, ALABAMA.

TYPE-WRITER LOCK.

1,174,304.

Specification of Letters Patent.

Patented Mar. 7, 1916.

Application filed March 12, 1915. Serial No. 13,931.

To all whom it may concern:

Be it known that I, MILTON M. BLUM, a citizen of the United States of America, residing at Birmingham, in the county of Jefferson and State of Alabama, have invented certain new and useful Improvements in Type-Writer Locks, of which the following is a specification.

My invention relates to a novel means for providing typewriters with a permanent lock attachment by means of which the carriage of the keys or both may be locked at will so that the machine cannot be operated by an unlicensed party.

The chief object of my invention is to equip the machine with a simple and inexpensive lock attachment by means of which the operator can lock a machine to prevent it being tampered with or operated during his or her absence.

Another advantage of my invention is that in shipping the machines my lock will hold the carriage and practically all of the movable parts in position to prevent injury to them and to save the expense and trouble of tying the parts down as is now the general practice.

A further object of my invention is to adapt a single lock to simultaneously control the locking of both the carriage and the type bar levers, thereby locking all operating moving parts at a single operation and with a single key.

My invention further comprises the novel details of construction and arrangement of parts which in their preferred embodiment only are hereinafter more particularly described and illustrated by reference to the accompanying drawings which form a part of this specification, and in which:

Figure 1 is a side elevation of the forward end of a typical typewriter with the frame broken away to illustrate the lock mechanism in front elevation. Fig. 2 is a vertical sectional view taken on the line $x-x$ of Fig. 1. Fig. 3 is an enlarged internal view taken on the line $y-y$ of Fig. 2, and showing the rear wall of the lock casing broken away to illustrate the lock mechanism.

Similar reference numerals refer to similar parts throughout the drawings.

I have illustrated my invention as applied to a Remington type of machine but it will be understood that it can be modified within the scope of my invention for application to any of the present standard types of ma-

chines which embody the depressible type bar levers and a movable carriage.

As illustrated, the typewriter frame comprises a bed plate 1, a top plate 2, and vertical posts 3, which connect the top and bed plates. The machine is provided with a plurality of type bar levers 4 of standard design which are hinged to the frame in the customary manner (not shown). On the top plate 60 2 I mount posts 5 which support the transverse run way 6 which receives and guides the forward transverse member 7 of the transversely slidable carriage 8.

My lock mechanism in its preferred embodiment comprises a lock casing 9 preferably rectangular in form and provided with a side flange 10 adapted to be inserted behind and riveted to the inner flange 11 of one of the vertical posts 3, the bottom edge 70 of the lock being supported on the upper edge of a side plate 1. This gives a firm and rigid mounting for the lock casing and disposes it at a point where it is concealed from view yet convenient for the operations contemplated to be performed by it. The lock 80 illustrated is of the Yale lock type comprising a barrel 12 adapted to receive a key 13. The cylinder of this barrel, which is of ordinary design and therefore not illustrated, 85 has attached to it a disk 14 (Fig. 3) on the outer edge of which is a pin 15. This disk works in the casing 9 and its pin engages in the curved slot 16 formed in a vertically movable sliding lock plate 17, which lock 90 plate at one side is formed integrally with or is rigidly connected to lock rods 18 and 19. These may be formed by one continuous rod or by integral extensions of the plate 17 or in any other suitable manner so long 95 as the rods 18 and 19 are connected to the lock plate 17 for vertical movement therewith. The rods project through suitable openings provided in the top and bottom walls of the casing, the rod 18 extending 100 vertically upward and through an opening 20 in the top plate 2. The transverse member 7 of the carriage is provided with a socket 21 in its under face in position to receive the upper end of the rod 18 when the latter is in raised position. The rod 19 has provided at its lower end a transverse eye 105 22 which receives the out-turned end of a crank 23. The crank is carried by a rocking lock member for the type bar levers, which 110 member comprises a transverse rod 24 preferably formed integral with the crank 23.

and having mounted thereon a wing plate 25. The rod 24 at its left hand end is pivoted in a suitable hole 26 formed in the left hand side 1 of the bed plate and its right hand end is 5 journaled in a depending extension 27 of the lock casing 9.

It will be noted in Fig. 3 that the pin 15 is in its upper position and is in engagement with a shoulder 28 provided in one wall of 10 the slot 16. If the key 13 is turned to swing the pin to the left (Fig. 3), the pin will travel through the slot 16 and force the plate to its lowered position, carrying with it the lock rods 18 and 19 and holding them in lowered 15 position.

As illustrated, the machine is locked, the lock plate 17 being set in raised position, the rod 18 being projected upwardly into the socket 21 so as to interlock with the carriage and prevent its movement, and the rod 19 being raised so that the pivoting movement imparted by it through crank 23 to the bar 24 will swing the wing member 25 thereof into vertical position under the type bar levers, as seen in full lines in Fig. 3, 20 so as to lock them against operation. On the reverse movement of the lock the rod 18 is lowered to clear the carriage and the rod 19 depressed to swing the wing member 25 to the dotted position shown in Fig. 3 25 in which the type bar levers are released for operation. This wing member can be cut away in any desired manner to provide for the manipulation of control parts while 30 leaving its key lever engaging surface of uniform width. While the locking rods 18 and 19 are arranged to operate simultaneously, it will be obvious that I can use either or both in conjunction with the lock 35 as conditions may require.

The carriage lock rod 18 can be bent or shaped in any suitable manner to take advantage of any openings that may already exist in the top plate 2 and which will give 45 access to any lock engaging part on the carriage. It will be understood that the type of locking mechanism that I have shown may be widely varied and that advantage may be taken in locking the type bar levers 50 of any lock bar member which may already be provided on the machine and which is capable of operation by the lock member in substantially the manner described in connection with the type of bar lever lock 25.

Having thus described my invention, 55 what I claim as new and desire to secure by Letters Patent, is:—

1. The combination with a typewriter frame, a platen carriage and type bar levers, 60 of a key controlled lock permanently attached to the side of the frame, and two separate locking means actuated by said lock, one of said means being adapted to engage and lock the carriage against the frame and the other being adapted to en-

gage and lock the type bar levers against operation.

2. The combination with a typewriter, of a platen carriage and type bar levers, of a key controlled lock permanently attached 70 to the typewriter, a carriage engaging detent, a lever stop lock means, and means operable by the key controlled lock to move the detent and lever stop lock means into position to prevent operation of the carriage 75 or type bar levers.

3. The combination with a typewriter having a carriage and type bar levers, of a key controlled lock permanently attached to the typewriter and comprising a key 80 operated actuator, a carriage locking member, and a type bar lever locking means, said member and means being operably connected to said actuator.

4. A typewriter lock mechanism, comprising a key controlled lock adapted to be permanently attached to the typewriter, a carriage lock device, a type bar lever locking device, a key actuated member, and means to connect said devices to and actuate them 90 by said key actuated member.

5. A typewriter lock mechanism comprising a lock having a key actuated member, a typewriter carriage, and a device movable with said member and adapted to engage 95 and interlock with said carriage to prevent its operation.

6. A typewriter frame, a movable carriage having a bottom keeper, a top plate over which the carriage moves, and a key 100 controlled lock attached to said frame below said top plate and having a bolt adapted to engage and interlock with said keeper, there being an opening in said top plate for the bolt to pass through, substantially as 105 described.

7. The combination with a typewriter, of a transverse pivoted swinging bar disposed below the type bar levers, a lock permanently attached to the typewriter, a key 110 actuated bolt which extends above and below the lock, a connection between said bolt and said bar to move the bar into the path of the type bar levers and lock them against operation, and a typewriter carriage having 115 a keeper adapted to interlock with the bolt.

8. The combination with a typewriter and its carriage, frame, and type bar levers, of a lock permanently attached to said frame and having a bottom extension, a crank 120 member disposed under said levers and journaled at one end in the frame and at its other end journaled in said extension of the lock, a carriage locking bolt operable by said lock, and means to connect said crank member 125 to said bolt, said member being movable by the bolt in its carriage locking position to prevent the operation of the type bar levers, substantially as described.

9. The combination with a typewriter 130

having a movable carriage, a top plate over which said carriage moves and which has an opening therein under the carriage, a lock means permanently attached to the typewriter, and a vertically movable lock pin operable by means of the lock and adapted to pass up through said opening in the top plate and interlock with the carriage to prevent its movement, substantially

5 as described.

10. In a typewriter lock mechanism, a lock permanently attached to the typewriter and comprising a key operated rotary member, a pin movable with said member and eccentric thereto, a vertical movable locking member having a curved slot in which said pin engages, and means co-acting with said lock member to lock the carriage and type bar levers against operation.

15

20 11. The combination with a typewriter

having a key lock bail and type bar levers, of a key controlled lock permanently attached to the typewriter, a bolt rod actuated by the lock to move and lock said key lock bail and prevent the manipulation of 25 the typewriter keys.

12. A typewriter carriage key lock mechanism comprising a lock casing adapted to be permanently attached to a typewriter and a key actuated bolt member adapted to 30 project in the path of and engage a part of the carriage to interlock it with the typewriter frame.

In testimony whereof I affix my signature in presence of two witnesses.

MILTON M. BLUM.

NOMIE WELSH,
R. D. JOHNSTON, Jr.

It is hereby certified that in Letters Patent No. 1,174,304, granted March 7, 1916, upon the application of Milton M. Blum, of Birmingham, Alabama, for an improvement in "Type-Writer Locks," an error appears in the printed specification requiring correction as follows: Page 1, line 12, for the word "of" read *or*; and that the said Letters Patent should be read with this correction therein that the same may conform to the record of the case in the Patent Office.

Signed and sealed this 2d day of May, A. D., 1916.
